UNITED STATES PATENT OFFICE.

EARL A. WHITE, OF URBANA, ILLINOIS.

MULTIPLE-TEAM HITCH.

1,333,234.

Specification of Letters Patent.

Patented Mar. 9, 1920.

Application filed February 3, 1919. Serial No. 274,636.

To all whom it may concern:

Be it known that I, EARL A. WHITE, a citizen of the United States, residing at Urbana, in the county of Champaign and State 5 of Illinois; have invented certain new and useful Improvements in Multiple-Team Hitches, of which the following is a specification, reference being had to the accompanying drawings, forming a part thereof.

10 The purpose of this invention is to provide apparatus for hitching a plurality of teams in tandem arrangement, and at the same time balancing the pull of each team against that of all the others, so that all will 15 take their proportionate shares of the load. The invention is also concerned with means for insuring substantially equal working conditions for all the teams, by controlling the angle of the traces with the ground. It 20 consists in the various features and elements and their combination as hereinafter described and shown in the drawings and indicated by the claims.

In the drawings:

25 Figure 1 is a diagrammatic side elevation of a multiple team hitch embodying this invention as arranged for five teams in tandem.

Fig. 2 is a diagrammatic plan view of the 30 arrangement shown in Fig. 1.

Fig. 3 is a diagram indicating the tendency of a tandem hitch to pull the traces away from the correct working angle.

Fig. 4 is a diagram showing the effect 35 of weights for holding the traces at correct working angle.

Fig. 5 is a detail side elevation of one 40 of the draft rods with associated pulleys and cable together with an equalizer or doubletree connected therewith for attachment of one of the teams.

Fig. 6 is a plan view of the parts shown in Fig. 5.

Fig. 7 is a plan view of a doubletree or 45 equalizer showing a method of applying weights thereto for controlling the angle of the traces.

Fig. 8 is a detail vertical section of a 50 doubletree with the cable and traces attached thereto, showing another method of applying weights for controlling the angle of the traces.

An apparatus embodying this invention is diagrammatically shown in Figs. 1 and 55 2 as arranged for five teams of horses; but

exactly the same principles may be applied and similar apparatus may be provided for hitching up either a smaller or larger number of teams in tandem. The pull of the horses is transmitted preferably through a 60 series of steel rods, 10, 20, 30 and 40, and finally through an eye or clevis, 50, or other suitable connector attached to the vehicle or implement to be drawn. Each team of horses is attached to the draft apparatus 65 by means of a doubletree, or, if more than two horses constitute a team, any other equivalent equalizer may be used, and these equalizers are indicated as to position in Figs. 1 and 2 at 11, 21, 31, 41 and 51 respectively. For purposes of further description a typical group of the apparatus has been shown in Figs. 5 and 6, these parts including the draft rod, 40, the equalizer or doubletree, 51, and a cable and pulleys associated therewith. The pull of the horses on the equalizer, 51, is transmitted through a rope or cable, 52, leading off from the pulley, 53, which is journaled in a block or carrier, 54, to which the clevis, 50, is connected. From the pulley, 53, the cable runs forward over a pulley, 55, in a block, 56, back to pulley 57, of the block, 54, and forward again over pulley, 58, from which the end of the cable leads off for attachment to the forward end of the block, 54, at 59; in the arrangement diagrammed in Figs. 1 and 2, the total pull of the five teams of horses upon the clevis 50 is transmitted through five strands of the cable, 52, and in accordance with the well understood rule governing this form of tackle, one-fifth of the pull is transmitted through each of these strands; thus it is evident that the team at the equalizer, 51, 90 will take one-fifth of the load, which is its proportionate share as among the teams.

By reference to Figs. 1 and 2, it will be seen that each succeeding set of pulleys ahead of those detailed in Figs. 5 and 6 has 100 one less strand of the cable transmitting the load; whereby each team is balanced against all the teams ahead of it and the aggregate pull of such team and those ahead of it is transmitted through the next following draft rod to the next set of pulleys, to be balanced against the following team. Thus, ahead of the draft rod, 20, there are only two teams, and the load is divided equally between them by means of a single pulley, 110

23, and cable, 22, passing around it, with one end attached to the doubletree, 21, and the other end attached through the draft rod, 10, to the doubletree, 11, of the leading team. 5 As soon as three or more teams are hitched in tandem, each additional pulley set will comprise two blocks of pulleys with one end of the cable always leading off forwardly from the rear block for attachment to a 10 doubletree or equalizer and with the other end of the cable leading off rearwardly from the forward block of pulleys or forwardly from the rear block of pulleys, this relation alternating as between adjacent pulley sets 15 in the total series, and depending of course upon the number of strands of cable required for properly transmitting and balancing the load at the different points.

Since the play of the cables about their 20 pulleys will permit each team to move backward or forward more or less with respect to the adjacent draft rod, it is desirable to keep that movement within proper limits and this may be done by providing each of 25 the rods with a ring or eye, 60, attached to the rod as in Figs. 5 and 6, and securing thereto a buck strap, 61, which is connected to the bridle of each horse by another strap in the nature of a check rein not shown. 30 Thus, if the team starts to advance too far ahead with respect to the draft rod, the pull on this buck strap, 61, will tend to check any further advance, thus incidentally preventing the two pulley blocks from being drawn 35 together too closely into conflicting relation.

Each end of the draft rod, 40, is formed with a hook or, preferably, a closed eye, 62, and the other draft rods may be exactly 40 similar in construction to permit connection with the pulley blocks. Any suitable coupling means may be employed, the drawings showing a swivel connector, 63, disengagably and pivotally attached to the pulley block, 56, by a coupling pin, 64, held in 45 place by a cotter pin, 65. A similar coupling pin, 66, secures the clevis, 50, to the pulley block, 54, or may be used to attach an additional swivel connector and one more draft rod, if another team is to be connected 50 in the series. Furthermore, the equipment shown in the drawings may at any time be adapted for less than five teams by merely detaching one or more of the rear sets of pulley blocks and draft rods, and replacing them with the clevis, 50, connected 55 to the rearmost block remaining. This does not involve unthreading any of the cables from their pulleys, but merely disconnecting each set of pulleys as a unit, and with it 60 one of the draft rods.

On farm vehicles and agricultural implements generally the equalizer or doubletree is mounted fairly close to the ground and held in this position by the weight of the 65 vehicle; ordinary draft harness is therefore

designed to connect the swingletrees of the equalizer in such position with the collars of the horses at an angle at which the horses can work effectively. However, upon harnessing several teams in tandem and thus 70 greatly elongating the line of draft, there is a tendency for the doubletrees of the forward teams to rise from the ground so much as to seriously change the angle of the traces with respect to the collars, as indicated in 75 the diagram of Fig. 3. This changes the direction of pull of the traces with respect to the collar, tending to choke the horse and sometime causing an upward pull upon the belly-band which forces the horse to work 80 under distress and not efficiently.

A feature of the present tandem hitch is therefore some means for holding the equalizers of the several teams at approximately 85 equal distances from the ground, so that the angle of trace shall be the same for each team of the series and shall be an efficient angle. This may be done as suggested in Fig. 4 by a weight at the connection between the doubletree and the cable leading 90 to each set of pulleys, such weight being indicated at 67. An enlarged detail view of the same arrangement in Fig. 8 suggests further that each weight may be made up of several units, so as to be varied if occasion requires. In Figs. 3 and 4 the collars are indicated at 68 and the traces at 69.

Fig. 7 shows a slightly different arrangement of the weights, in which, in the form of heavy metal disks, 70, they are secured on 100 top of the equalizer or doubletree at its pivotal points merely because the pivots at these points may also be utilized as the securing means. Obviously such weighting may be confined either to the mid-point of 105 the doubletree or to its ends, or the weights may be applied at all three positions as shown in Fig. 7. Figs. 5 and 6 illustrate a method of applying the weight to the rear pulley block of the set, at 71, these weights 110 also being made up of several units so as to be variable; obviously this arrangement would permit straightening out the line of draft through the trace and the cable leading to the rear pulley by holding each set of 115 pulleys close to the ground, resulting in uniformity of the angle of trace, and by employing slightly shorter traces than would be used with the other arrangements shown, the actual angle between the traces and the 120 collars might be made substantially the same as in those cases and equally effective.

I claim:—

1. In a draft linkage for hitching a plurality of teams in tandem, draft members 125 for transmitting the combined pull of the teams and equalizing devices for balancing the teams against each other arranged at longitudinally separated points in the linkage and provided with connections for at- 130

taching the respective teams at correspondingly separated points, together with supplemental weights applied to the linkage adjacent the several points of attachment of the teams for holding such points at approximately equal distances from the ground.

2. In a draft linkage as set out in claim 1, the said supplemental weights being variable for adjusting the linkage to different draft conditions at will.

3. In a draft linkage as set out in claim 1, the weights being applied adjacent the

double-tree or equivalent equalizer of each team.

4. In a draft linkage as set out in claim 1, the equalizing devices comprising pulley blocks connected adjacent the respective double-trees and the supplemental weights being in the form of apertured disks or plates secured to the sides of the pulley blocks.

In testimony whereof, I have hereunto set my hand at Urbana, Illinois, this 24 day of January, 1919.

EARL A. WHITE.
